UNITED STATES PATENT OFFICE.

RICHARD C. PETERSON, OF MALDEN, WASHINGTON.

MEANS FOR PREVENTING DOUBLE EXPOSURES.

1,289,256.

Specification of Letters Patent. Patented Dec. 31, 1918.

Application filed December 12, 1917. Serial No. 206,799.

To all whom it may concern:

Be it known that I, RICHARD C. PETERSON, a citizen of the United States, residing at Malden, in the county of Whitman and State of Washington, have invented certain new and useful Improvements in Means for Preventing Double Exposures, of which the following is a specification, reference being had to the accompanying drawings.

This invention relates to photographic cameras, and particularly to means for preventing double exposure.

In taking pictures with ordinary film cameras, double exposures are quite likely to occur, because of the operator forgetting to wind the film roll at the making of an exposure, so that the next exposure is made on the same film, thus ruining two pictures.

The general object of this invention is to remove all chances of double exposure by providing a member movable into an obstructing position by the action of snapping the shutter, but shiftable out of an obstructing position by the action of winding up the exposed film, this member being specifically either a shutter obstructing member or a finder obstructing member.

A further object of the invention is to provide a device of this character, which is so arranged that the finder on the camera may be shifted into either of its two positions, without requiring any adjustment of the attachment.

Still another object is to provide a device of this kind in which the mechanism is adjustable with all the adjustments of the camera, either for focusing the lens or for raising or lowering the lens.

And another object is to provide means whereby the indicator and the mechanism for actuating the indicator are actuated by the cable release or other shutter operating mechanism.

Other objects will appear in the course of the following description.

My invention is illustrated in the accompanying drawings, wherein:

Figure 1 is a front view of a film camera equipped with one form of finder and having my attachment applied thereto;

Fig. 2 is a side view of the camera illustrated in Fig. 1, the parts being broken away;

Fig. 3 is a side elevation of the clutch device, the adjacent portions of the camera being in section;

Fig. 4 is a front elevation of the clutch device shown in Fig. 3;

Figs. 5 and 6 are diagrammatic vertical sections through the clutch showing the operation of the clutch, these views being taken on the line 5-5 of Fig. 4;

Fig. 7 is a fragmentary sectional view showing the clutch connection on the shaft;

Figs. 8 and 9 are front elevations of another form of finder showing my attachment applied thereto, a portion of Fig. 9 being broken away;

Fig. 10 is a perspective view showing the indicating arm and the connecting rod for operating it;

Fig. 11 is a fragmentary vertical sectional view showing the ring in which this indicating arm is mounted;

Fig. 12 is a vertical sectional view through one wall of the camera on the line 12-12 of Fig. 2;

Figs. 13 and 14 are detailed fragmentary views showing the application of my device to another form of finder;

Fig. 15 is a perspective detailed view of one of the racks and the signal or indicator actuating arm coacting therewith;

Fig. 16 is a perspective view of a modified form of indicator;

Fig. 17 is a face view of part of the shutter mechanism of the camera showing my mechanism applied to locking the shutter; and

Fig. 18 is a vertical longitudinal section through the mechanism illustrated in Fig. 17.

Fig. 19 is a view showing in side elevation the clutch connection to the indicator and the winding key and a flexible shaft 86 extending from the pinion actuated by the winding key to clutch connection.

As before stated, the general object of this invention is to prevent double exposures by providing an indicator or signal 100 which, when an exposure is made, is automatically shiftable to a position across the finder, so that if the photographer desires to take another photograph and has not wound up the film so as to present a new 105 film for exposure this fact will be indicated by the presence of the indicator extending across the finder. There are a number of different forms of finders used in connection with various makes of film carrying 110 pocket cameras and, therefore, in the accompanying drawings, I have illustrated how

my invention may be applied to finders of different types. I have only illustrated one form of finder in connection with the complete camera, but it is to be understood that 5 the various forms of finders which will be hereafter described may be used with this camera, without changing the indicator actuating mechanism to any large extent, as will be later described.

10 Referring now to Figs. 1 and 2, it will be seen that I have illustrated a folding camera of the ordinary type consisting of a body 10, the bellows 11, a lens carrying plate 12 and a door 13 upon which this lens carrying plate is operatively supported as by means of brackets 14. It is to be understood that these parts may be of any suitable construction and that the attachment is not limited to use with a camera constructed as indicated in the drawing. The bracket 14 is, as usual, adjustable in slides toward or from the body 10 so as to secure the proper focusing of the lens and also to permit the bellows and the lens plate with 25 the lens to be inclosed within the body 10, but this mechanism whereby the bellows is contracted or expanded and whereby the lens plate is held in adjusted positions on the door 13 is not illustrated as it is of the ordinary type and forms no part of my invention.

30 The shutter of the lens is operated by means of the usual cable release 15. The tube of this cable release, however, is branched, one branch extending to the operating mechanism of the shutter and the other branch extending to a point beneath the finder 17 in Figs. 1 and 2. This branch 35 is provided at its extremity with a head 18, which is shiftable outward upon an actuation of the cable release, this head being provided with a shank which operates in any suitable guide. It will thus be seen that coincidently with the operation of the shutter the head 18 is shifted outward.

40 The finder 17 illustrated in Figs. 1 and 2 is of that type wherein a frame rotates around a relatively fixed lens, this lens being supported in a lens ring 19. Mounted on the inside of the lens supporting ring 19 is an indicator 20, illustrated in Fig. 10, this indicator being pivoted as at 21 and having an outwardly projecting arm 22. A connecting rod 23 is pivotally connected to the 45 extremity of this arm 22, the arm 22 acting as a crank arm. When the arm 23 is drawn in one direction, the curved indicator or signal 50 20 will be thrown up to a position across the lens, as illustrated in Fig. 1 and when the rod 23 is thrown in the opposite direction, the indicating arm will be shifted to a position where it leaves the sight opening through the lens entirely unexposed.

55 Mounted upon the supporting plate 12 of the camera is a shaft 24, which extends to-

ward the body of the camera and is disposed beneath the finder, this shaft 24 carrying at one end an eccentric 25. The extremity of the connecting rod 23 remote from the signal arm 20 is preferably provided with an eccentric ring 26, which engages with the eccentric 25. It will be obvious now that upon an oscillation of the eccentric, the connecting rod 23 will be shifted to project the indicator into the field of the finder lens or 70 retract the indicator from said field. Mounted upon the extremity of the shaft 24, as illustrated in Fig. 7, is a beveled gear wheel 27. In Figs. 8 and 9 I show a finder wherein the lens 29 and the body 28 of the 75 finder rotates within a frame 30. This is a common type of finder mounting and needs no further description, but in this case I make the frame 30 U-shaped in cross section and the indicator 20, which is the same as 80 the indicator previously described, is mounted upon this relatively fixed frame 30 between the sides thereof. This indicator 20, of course, is pivoted at 21 and has the arm 22 and the connecting rod 23 carrying an eccentric ring at its lower end. For the purpose of rotating the shaft 24, I provide a sliding rack 18^a, engaged by the head 18, and a toothed gear 24^a with which the rack 18^a engages.

95 Extending parallel to the plate 12 and disposed inward thereof, is a shaft 31, which is preferably made in two telescopic sections, as in many forms of camera, the camera plate is vertically adjustable. Where the 100 camera plate is not vertically adjustable, the shaft 31 may be made in one section. The lower end of the shaft 31 carries upon it a beveled gear wheel 32 and mounted upon the door 13 is a shaft 33, the outer end of this 105 shaft carrying a relatively elongated gear cylinder 34, that is, a gear wheel which is relatively elongated. This shaft 33 is mounted in suitable bearings and is preferably in two sections, the sections having 110 telescopic engagement with each other and rotative engagement with each other.

115 Mounted upon the bracket 14 or in any other suitable manner, is a short horizontal shaft 35, carrying on one end a beveled gear wheel 36 which engages the beveled gear wheel 32, and carrying at its opposite end the gear wheel 37, which engages with the toothed cylinder 34. It will thus be seen that as the cylinder 34 is rotated, it will 120 cause the rotation of the shaft 31 and a rotation of the shaft 24, and it will likewise be seen that the toothed cylinder 34 which constitutes an elongated gear wheel permits the adjustment of the lens supporting plate to 125 secure the proper focus for the camera, the gear wheel 35 shifting along the elongated teeth of the cylinder 34. The shaft 33 is connected by a flexible joint 38 to a short shaft section 39, carrying at its rear end a 130

beveled gear wheel 40. Disposed in the end wall 41 of the camera is a shaft 42, which carries at its lower end a beveled gear wheel 43, engaging in turn with a beveled gear wheel 44, mounted upon a shaft 45, which extends inward through the side wall 41, this shaft 45 carrying upon it a beveled gear wheel 46, which engages with the beveled gear wheel 40. At its upper end the shaft 42 carries a beveled gear wheel 47, which is disposed in a recess 48 opening upon the face of the end wall. Disposed in the face of this end wall is the usual cup-shaped metallic ferrule 49, through which the usual winding shaft 50 of the camera passes. This winding shaft carries a key 51, whereby it may be rotated, this key being foldable into the depression formed by the cup-shaped ferrule 49. Mounted upon this shaft 50 is a beveled gear wheel 52, which meshes with the gear wheel 47, and thus it will be seen that when a film is wound up in the usual manner by rotating the key 51, the shaft 42 will be rotated, and this will rotate the shafts 45 and 39, and this, rotating the shaft 33, will cause a corresponding rotation of the shaft 31 and a rotation of the shaft 24 which will carry the indicating finger out of its exposed position and into its unexposed position.

I have described the gear wheel 40 as if it were directly mounted upon the shaft section 39, but in order to prevent more than a quarter turn of the shaft 24, I have provided a peculiar clutch member illustrated in Figs. 3 and 4. Loosely mounted upon the shaft 39 is the gear wheel 40, as previously described, and this gear wheel is provided with a hub 53 formed with clutch teeth 54. Slidably mounted upon the shaft 39 to turn therewith is a clutch member 55 having clutch teeth engaging with the teeth 54, this clutch member being urged into engagement with the teeth 54 by means of an internal spring 56. This clutch member 55 is provided, as illustrated in Fig. 4, with a radially projecting arm 57. Mounted upon the base wall of the camera and arching over the shaft section 39 and specifically over the clutch member 55 in concentric relation thereto, is a bracket 58, and mounted upon this bracket is an arcuate bar 59, having an angular length equal to one quarter of a circle. In other words, equal in angular length to the angular movement of the indicating arm 20. Consequently, if the arm 20 moves to an extent greater than 90°, the bar 59 extends through a length greater than 90° and vice versa. Disposed behind the bar 59, and parallel thereto, but extending beyond the lower end of the bar 59, is a spring 60, the lower end of this spring being outwardly turned as illustrated in Figs. 5 and 6. This spring is spaced from the inner face of the bar 59 a sufficient distance to receive the pin or arm 57.

Normally, that is, before the exposure is made, the pin 57 is disposed in the dotted line position in Fig. 4, and in the position shown at *a* in Figs. 5 and 6. The exposure is made and the movement of the shaft 24 through a quarter circle caused by the sliding movement of the rack bar 18, through the gears 27, the shaft 31 and the gears 32, 35 and 37 and allied parts, rotates the shaft 39 in a clockwise direction so as to carry the pin or arm 57 from the lower end of the bar 59 upward and beyond the upper end of the bar, the clutch member 55 being held out of mesh with the teeth 54 by this bar 59, which constitutes a guard. When the pin 57 has passed the upper end of the member 59, the spring 56 will cause the clutch member to move inward and engage with the clutch teeth 54.

Now when the exposed film is wound up, the rotation of the key 51 causes a rotation of the gear wheel 40 in a counter-clockwise direction and the arm 57 on the clutch 55 will move down, as illustrated in Fig. 5, between the inner face of the member 59 and the spring 60. The clutch member will remain in engagement with the teeth 54 until the pin 57 has passed beyond the lower end of the member 59, when the deflected lower end of the spring 60 will shove the pin 57 outward, shifting the clutch 55 outward against the force of the spring 56 and disengaging the clutch member from the teeth 54, it being understood that the spring 60 is stronger than the spring 56. Thus the clutch member will be disengaged from the gear wheel 40, after the clutch member and the shaft section 39 has made a quarter rotation, which will bring the indicator 20 back to its initial position. A further rotation of the film winding spool and of the shafts 41 and 45 will not, therefore, affect the shaft section 39. In other words, the object of the particular form of clutch illustrated in Figs. 3 and 4 is to prevent any rotation of the shaft 39 and of the parts connecting this shaft with the indicator beyond a quarter turn or a movement sufficient to shift the indicator from its effective indicating position to its ineffective position.

While I have illustrated the clutch shown in Fig. 3 as being disposed upon the shaft section 39 and adjacent to the gear wheel 40, I wish it to be understood that this clutch might be disposed anywhere between the gear wheel 40 and the indicator. Thus it might be used between the gear wheel 27 and the forward end of the shaft 24, and in this case, there will be less resistance offered to the movement of the plunger 18 than is the case where the clutch is disposed as in Fig. 3. Other means may be provided as will be now stated for operatively disconnecting the shaft 24 from the train of gears.

In Fig. 7, I show a much simpler con-

struction, which may be used for the purpose above stated. In this figure, the shaft 24 has loosely mounted upon it the gear wheel 27, and this gear wheel 27 is oper-
 5 atively engaged with the shaft 24 by means of what is practically a friction clutch comprising a member 61, slidably mounted upon the shaft 24 and splined thereto and urged toward the clutch member 62 carried by the
 10 gear wheel 27, the clutch members 61 and 62 being provided with relatively shallow clutch teeth which may readily slip by each other when there is a considerable impediment to movement. With this construction,
 15 when the key 51 is turned, rotation will be transmitted in the manner heretofore described, to the gear wheel 27, and inasmuch as the work to be done by the rotation of the shaft 24, that is, the shifting of the indicator 20, is relatively light, the clutch members 61 and 62 will be held in engagement with each other and the shaft 24 will rotate with the gear wheel 27 until such time as the indicator has reached its re-
 20 tracted position. A stop 63 may be provided on the shaft 24, which will engage with a fixed stop 63^a when the shaft 24 has made a quarter revolution and when these stops are engaged with each other and the
 25 shaft can rotate no farther, because the indicator has been thrown to its fully retracted position, then the continued revolution of the gear wheel 27 will cause the clutch faces of the clutch members 61 and 62 to shift past each other. When an exposure is made and the plunger 18 is shifted to shift the rack 18^a which engages the gear wheel 24^a on the shaft 24, the shaft 24 will rotate, but the resistance to the rotation of the gear 27 will be so great, due to the train of gears and shafts connected thereto, that the clutch members 61 and 62 will slip on each other and there will be relatively slight impediment to the movement of the shaft 24. While I have illustrated a particular form of friction clutch, it will be understood that other forms of clutches equivalent in operation thereto may be used.
 30 In Figs. 13, 14 and 15 I show the manner in which my mechanism is applied to a camera wherein the finder frame itself is pivoted upon the camera and is rotated upon this pivot in order to turn the finder into a position for taking horizontal pictures or vertical pictures, that is, in the first instance, pictures where the longer axis of the camera is arranged horizontally, and, in the second instance, where the longer axis of the camera is arranged vertically. In this figure, 64 designates the finder frame carrying the usual lens and pivoted at 65 upon a bracket 66 projecting out from the body of the camera. In Fig. 13 the finder is illustrated as in a position to take pictures whose

extreme length extends vertically, while in Fig. 14 the finder is shifted so as to take pictures where the length of the picture runs horizontally.

Mounted upon the shaft 24 is a gear wheel 70 70 67, which meshes with a gear wheel 68 of the same size. This gear wheel 68 is mounted in a frame 69 having a guide 70, which extends vertically and a guide 71 which extends horizontally, the vertical guide 70 being adjacent the margin of the gear wheel 68, while the guide 71 extends horizontally adjacent the gear wheel 67. Slidably mounted on the guide 71 is the rack 72 having an outwardly projecting pin 73, and slidably 75 mounted on the guide 70 is the rack 74 having an outwardly projecting pin 75. The indicator arm 20 is pivoted to the camera frame and has an outwardly projecting arm 76 having a pin 77 which engages in the 80 angular slotted end 78 of a connecting rod 79, which is equivalent to the connecting rod 23. This connecting rod 79 moves in a guide 80 fast upon the face of the finder frame 64. The lower end of this connecting rod 90 79 is provided with a head 81, which is disposed in an inclined relation to the axis of the rod 79, this head being notched or bifurcated at its opposite ends as at 82 and 83.

With the parts as above described, when 95 the finder is in a position to take vertical pictures, the notch 82 will engage with the pin 73 on the rack 72 and a rotation of the shaft 24 and a consequent rotation of the gear wheel 67 will cause the rotation of the 100 gear wheel 68 and this will cause an upward movement of the rack, which will cause the signal arm 20 to shift to the position shown in Fig. 13 and across the lens of the finder. A counter-rotation of the shaft 24 will 105 cause a retraction of the indicator arm 20 to the position shown in dotted lines in Fig. 13. Now when the finder is turned into the horizontal position shown in Fig. 14, the rod 79 will swing with the finder through a 110 quarter circle so that the notch 83 will engage with the pin 75 on the rack 74. Then upon a rotation of the shaft 24 the gear wheel 67 will cause the rack 74 to move toward the right in Fig. 14, causing the indicator to move from its concealed position to its exposed position. As illustrated in Fig. 15, the guides 70 and 71 are preferably formed of strips of metal and the racks 72 and 74 are formed with T-shaped slots 84 115 120 to receive the guides. Of course it is to be understood that the shaft 24 carries the gears heretofore described and that the remainder of the mechanism is precisely the same as is indicated in Figs. 1 and 2.

While I have heretofore described means whereby an obstructing member is shifted across the field of the finder in order to obstruct the view therethrough until such time as the film is wound for the new ex- 125 130

posure, I do not wish to limit myself to an obstructing member of this character, and in Fig. 17 I have illustrated another form of obstructing member, which is shiftable into engagement with part of the shutter mechanism, to thereby hold the shutter from actuation by the cable release until such time as the film is rewound for the successive exposure. In this figure, 83 designates a member which is part of an ordinary shutter actuating mechanism, this member being pivoted at 84, and when the cable release is actuated, this member is shifted from its full line position to its dotted line position and back again. I have not illustrated any other portion of the shutter or shutter operating mechanism, as I do not deem it necessary to do so. Coacting with the member 83 is a shaft 85 which carries upon its inner end the gear wheel 86 which is engaged by the rack 18^a which in turn is engaged by the plunger 18 at the end of the branch 16 of the cable release 15. The gear wheel 86 corresponds to the gear wheel 24^a in Figs. 2, 8 and 9 and it is to be understood that the shaft 85 carries upon it the gear wheel 27, and the mechanism for connecting this gear wheel to the winding shaft 50, all as previously described.

Mounted upon the end of the shaft 85 is a sleeve or shaft section 87 which can rotate independently of the shaft 85 but is connected to the shaft 85 to rotate therewith by an internal coil spring 88. Carried upon the end of the sleeve 87 is a locking arm or latch 89. Now when the rack 18^a is shifted toward the right in Fig. 17, a clockwise rotation will be communicated to the shaft 85 which will cause the latch arm 89 to move downward. At the same time the member 83 is shifted upward by the action of the cable release, and meets and engages with the latch arm 89 when this latch arm has moved but a fraction of its full movement. The shaft 85 continues to rotate in a clockwise direction, but the sleeve 87 is held from rotation and the spring 88 is placed under tension. As soon, however, as the member 83 returns to its full line position in Fig. 17, where the shutter has been closed again, the spring 88 being under tension will cause a rotation of the latch arm 89 to a locking position where it is disposed vertically and rests upon the member 83 and prevents this member from again being actuated by the cable release until the film has been wound up. A winding up of the film will rotate the shaft 85 in a counter-clockwise direction and this will carry the locking arm 89 to its approximately horizontal position again and release the shutter mechanism so that it may be again actuated by the cable release.

It will be seen that in all forms of my construction, the actuation of the shutter actu-

ating mechanism will cause the operation obstructing device to shift to an obstructive position, and that the obstructing device will remain in this position until the exposed film is wound up. The first quarter turn 70 of the film winding shaft will cause the obstructing device to be shifted to a retracted or unexposed position and it will remain in this position until another exposure is made.

While I have illustrated a particular embodiment of my invention which I believe to be particularly effective, I wish it understood that various changes might be made in the details of the mechanism and the arrangement of the parts without departing 75 from the spirit of the invention. Thus it is possible to use a flexible shaft between the winding key shaft 50 and the shaft 24 of the shaft 85 and in Fig. 19, I show a connection of this character. In this figure, 80 27 designates the gear wheel carried by the clutch member 62 mounted upon the shaft 24, this shaft being provided in turn with a gear wheel which is rotated by the rack 18^a, as illustrated in Fig. 7 and Fig. 18 but 85 this beveled gear wheel 27 is driven by a beveled gear wheel 90 operatively connected to a flexible shaft 91, which extends from the bracket 92 into the interior of the camera casing and through a bracket 93 mounted on 90 the wall of the camera casing. This flexible shaft at this end carries a beveled gear wheel 94 engaging with a beveled gear wheel 95 provided with a shaft 96 extending through the wall of the camera box, this shaft 96 100 carrying a gear wheel 97 engaged by a gear wheel 98 mounted on the winding shaft 50, which carries the winding key 51. It will be obvious that the operation of this mechanism will be precisely the same as that 105 heretofore described, without the complication caused by the use of the shafts 42, 45, 33, and 31. A rotation of the key 51 in Fig. 19 will cause a rotation of the flexible shaft 91, and this in turn will cause a rotation of the gear wheel 27 and the shaft 34 to carry the indicator 20 of the finger 89 back to its normal position, after which the clutch yields so that a continued rotation of the clutch will not further shift the indicator or the finger. The movement of the indicator or the finger, by actuating the shutter release, does not of course affect the shaft 91.

Having thus described my invention, what 110 I claim is:—

1. The combination with a camera having a shutter operating device and a finder, of an indicator pivotally mounted upon the finder and shiftable into a position out of the field 115 of the finder or into said field, and means for operating said indicator comprising a sliding bar operatively engaged with the indicator to rotate it upon the shifting of the bar in one direction, said bar being operatively en- 120

gaged by the shutter operating device upon an actuation of the device to open and close the shutter of the camera.

2. The combination with a camera including a finder and a cable release, said cable release having a branch including a plunger, of an indicator movable into position across the field of the finder or out of such position, and a slide operatively engaged with the indicator to shift it and engaged by the plunger when the latter is operated by the cable release into operative position upon the movement of the slide in one direction, said plunger normally abutting against the slide and shifting the slide to carry the indicator into operative position upon the actuation of the cable release.

3. The combination with a camera including a finder and a cable release, said cable release having a branch including a plunger provided with a head, of an indicator movable into position across the field of the finder or out of such position, a slide operatively engaged with the indicator to shift it, and means for automatically returning the indicator to its inoperative position upon the winding up of the exposed film within the camera.

4. The combination with a camera having a film winding roll, a finder and a shutter operating cable release, of means for preventing double exposures comprising an indicator pivotally mounted upon the finder and shiftable into or out of a position across the field of the finder, means actuated by the cable release for shifting the indicator into its operative position across said field, and means actuated by a rotation of the roll causing the retraction of said indicator.

40 5. The combination with a camera having a film winding roll, a door shiftable into or out of a position at right angles to the camera, a bellows, a lens supporting member mounted on the bellows slidably engaged with the camera, a finder mounted thereon, and a branch cable release for actuating the shutter of the camera, of means for preventing double exposure comprising an indicator pivotally mounted upon the finder and shiftable into or out of a position across the finder, a member operatively engaged with the indicator to cause it to move into operative position, a plunger carried in one of the branches of the cable release and engageable with said sliding member upon an actuation of the cable release, and means for returning the indicator to its initial position comprising a shaft mounted upon the door of the camera, a shaft geared therewith and mounted upon the lens support and operatively engaged with said slide and with the first named shaft, a shaft mounted inside the body of the camera and operatively engaged to rotate with the film winding roller, operative connections between said last named shaft and the first named shaft to cause a rotation of the first named shaft and a retraction of the indicator upon a rotation of the film winding roller, said connections including coacting clutch members, a spring urging said clutch members toward each other, and means causing a disengagement of the clutch members after a predetermined rotation of the first named shaft.

6. The combination with a camera having a film winding roll, a door shiftable into or out of a position at right angles to the camera, a bellows, a lens supporting member mounted on the bellows slidably engaged with the camera, a finder mounted thereon, and a branch cable release for actuating the shutter of the camera, of means for preventing double exposure comprising an indicator pivotally mounted upon the finder and shiftable into or out of a position across the field of the finder, a member operatively engaged with the indicator to cause it to move into operative position, a plunger carried in one of the branches of the cable release and engageable with said sliding member upon an actuation of the cable release, and means for returning the indicator to its initial position comprising a shaft mounted upon the door of the camera, a shaft geared therewith and mounted upon the lens support and operatively engaged with said slide and with the first named shaft, a shaft mounted inside the body of the camera and operatively engaged to rotate with the film winding roller, operative connections between said last named shaft and the first named shaft to cause a rotation of the first named shaft and a retraction of the indicator upon a rotation of the film winding roller.

6. The combination with a camera having a film winding roll, a door shiftable into or out of a position at right angles to the camera, a bellows, a lens supporting member mounted on the bellows slidably engaged with the camera, a finder mounted thereon, and a branch cable release for actuating the shutter of the camera, of means for preventing double exposure comprising an indicator pivotally mounted upon the finder and shiftable into or out of a position across the field of the finder, a member operatively engaged with the indicator to cause it to move into operative position, a plunger carried in one of the branches of the cable release and engageable with said sliding member upon an actuation of the cable release, and means for returning the indicator to its initial position comprising a shaft mounted upon the door of the camera, a shaft geared therewith and mounted upon the lens support and operatively engaged with said slide and with the first named shaft, a shaft mounted inside the body of the camera and operatively engaged to rotate with the film winding roller, operative connections between said last named shaft and the first named shaft to cause a rotation of the first named shaft and a retraction of the indicator upon a rotation of the film winding roller, said connections including coacting clutch members, a spring urging said clutch members toward each other, and means causing a disengagement of the clutch members after a predetermined rotation of the first named shaft.

7. The combination with a camera having a film winding roll, a finder, and a shutter actuating device, of an indicator mounted upon the finder and movable into a position across the field of the finder and shiftable into such position by an actuation of the shutter actuating device, and means for returning the indicator to an inoperative position upon a rotation of the roll to wind up a film and including coacting clutch members, one of said clutch members being operatively connected to the winding roll and the other being operatively connected to the indicator to cause its rotation, a spring urging the clutch members into engagement with each other, an arcuate guide, a pin carried by one of said clutch members and engaging on one side of said guide when the clutch members are in engagement, and a spring stronger than the first named spring extending behind the arcuate guide and beyond it to cause a pin to be forced into a plane beyond the outer face of the guide when the pin has passed the lower end of the guide, said first named spring forcing the clutch members into engagement with each other after the

pin has passed the lower end of the second named spring.

8. The combination with a camera having a door movable into or out of a position at 5 right angles to the body of the camera, a bellows, a member slidably mounted upon the door and supporting the forward end of the bellows and the lens thereon, a shutter operating device including a cable release, 10 a film winding roller, and a finder, of means for preventing double exposures comprising an indicator mounted upon the finder and shiftable into or out of a position across the field of the finder, a rack, a plunger engaging 15 the rack upon a movement in one direction and actuated by the cable release, a gear wheel engaging the rack, a shaft upon which the gear wheel is mounted having an eccentric thereon, a rectangular yoke engaging 20 said eccentric and having an arm operatively engaging the indicator to shift it as the yoke is drawn in one or the other direction by a rotation of the eccentric, and means engaged by the film winding roller 25 and operatively engaging the shaft to rotate it in an opposite direction to retract the finder.

9. The combination with a camera, comprising a body, a door shiftable into a position at right angles to the body, a bellows, a bellows and lens support slidably mounted upon the door, a shutter actuating device, and a finder, of means for preventing double exposures including an indicator shiftable 30 across the field of the finder, means actuated by the shutter actuating device for shifting the indicator across the field, and means for returning the indicator to its original position comprising a film winding roller, a 35 shaft actuated thereby, a shaft mounted upon the door and parallel thereto and operatively engaged by the first named shaft, said second named shaft having a relatively long gear wheel, and a shaft mounted upon 40 and shiftable with the bellows supporting member operatively engaged at its upper end with the indicator, and a gear wheel operatively engaging the lower end of the 45 shaft and engaging with the longitudinally shaft and engaging with the longitudinally 50 extended gear wheel on the first named shaft.

10. The combination with a camera having a film winding roller, a finder, and a shutter operating member, of means for preventing double exposures comprising an indicator mounted upon the finder and shiftable into or out of a position across the 55 finder, means actuated by the shutter operating means for shifting the indicator into 60 its operative position across said finder, and means actuated by a rotation of the film winding roller, causing the retraction of said indicator, said means becoming operatively disengaged from the indicator upon 65 a full retraction of the indicator.

11. The combination with a photographic camera having a film winding roll and a shutter operating device, of a movable obstructing member normally in a non-obstructing position, operatively engaged by 70 the shutter operating device upon its operation and shifted to an obstructing position, and means operatively connecting the obstructing member and the film winding roll whereby power is transmitted from the film 75 winding roll to the obstructing member to rotate it to its inoperative position upon turning the roll to wind up an exposed film.

12. The combination with a photographic camera having a film winding roll and a shutter operating device, of an obstructing member in the form of an arm rotatable from a non-obstructing to an obstructing position and vice versa, means operatively 80 engaging the shutter operating device with 85 said obstructing member to shift it to an obstructing position upon the operation of the shutter operating device independently of the film winding roll, and means operatively connecting the obstructing device and 90 the film winding roll whereby the obstructing member is returned to its initial inoperative position upon turning the roll to wind up an exposed film and including a shaft operatively engaged with the obstructing member and with the film winding roll. 95

13. The combination with a camera having a film winding roll and a shutter operating member, of means for preventing double exposures comprising an operation obstructing member mounted upon the camera and shiftable into or out of an obstructing position, means actuated by the shutter operating means for shifting the obstructing member into its operative and obstructive 100 position, and means actuated by a rotation of the film winding roll for causing a retraction of the obstructing member to its initial non-obstructing position, said means becoming operatively disengaged from the 105 obstructing member upon a full retraction of the obstructing member to its initial position. 110

14. A camera having a body, a door hinged thereto, a bellows attached to the body and mounted upon the door, a film winding roll mounted on the body, an operation obstructing member carried on the lens mount and normally in a non-obstructive position, means for operating the shutter mechanism 120 and simultaneously shifting the obstructing member to its obstructing position, and means acting upon a rotation of the film winding roll for causing the obstructing member to return to its non-obstructing position and including shafts mounted upon the door and upon the camera body, the last named shaft being operatively connected to the film winding roll, and beveled gear wheels operatively connecting the shafts, 125 130

one of said wheels being disposed concentrically to the axis of rotation of the door.

15. A camera having a body, a door hinged thereto, a bellows attached to the body and 5 mounted upon the door, a film winding roll mounted on the body, an operation obstructing member carried on the lens mount and normally in a non-obstructive position, means for operating the shutter mechanism 10 and simultaneously shifting the obstructing member to its obstructing position, and means acting upon a rotation of the film winding roll for causing the obstructing member to return to its non-obstructing position and including shafts mounted upon 15 the door and upon the camera body, the last named shaft being operatively connected to

the film winding roll, and beveled gear wheels operatively connecting the shafts, one of said wheels being disposed concentrically to the axis of rotation of the door, the means for causing a retraction of the operation of the obstructing member to its non-obstructing position becoming operatively disengaged from said member when 25 the member has been completely returned to its inoperative position.

In testimony whereof I hereunto affix my signature in the presence of two witnesses.

RICHARD C. PETERSON.
